UNITED STATES PATENT OFFICE.

JOHN H. CROWELL, OF VINEYARD HAVEN, MASSACHUSETTS.

PRESS.

1,148,445.

Specification of Letters Patent. Patented July 27, 1915.

Original application filed March 29, 1912, Serial No. 687,206. Divided and this application filed March 21, 1913. Serial No. 756,018.

To all whom it may concern:

Be it known that I, JOHN H. CROWELL, a citizen of the United States, residing at Vineyard Haven, in the county of Dukes and State of Massachusetts, have invented a new and useful Press, of which the following is a specification.

This application is a division of my application Serial Number 687,206, filed March 10 29, 1912, on which Letters Patent No. 1,076,023 were issued October 21, 1913.

The purpose of my invention is to provide a press usable as a combined foot and screw press.

15 To these ends my invention consists in the new and novel construction, combination and arrangement of parts hereinafter described, and illustrated in the accompanying drawings, in which,

20 Figure 1 is a front elevation of a press embodying my invention. Fig. 2 is a side elevation of the same, partly in section.

Like reference letters and numerals indicate like parts where they occur in the drawings.

25 Referring to the drawings, A represents the frame, comprising upright members, as A¹, and a cross member A² connecting them at their upper ends. These parts are preferably integral, and are mounted upon a table A³, in turn supported on legs or standards, as A⁴. Said uprights are fitted to serve as guideways in which a follower 1 is fitted for reciprocal vertical movement: as 30 actuated as hereinafter described. Said follower is provided with a transverse medately disposed perforation into which extends the prolonged upper end or arm 2¹ of the treadle 2 pivotally mounted upon and 35 between said uprights, and below said cross member. Said cross member is provided with a centrally disposed perforation, internally threaded, for the operation there-through of an externally threaded screw 3, 40 carrying upon its upper end an operating handle 4 in turn carrying a counterweight 4¹. To the lower end of said screw I secure the follower 1. A collar and set screw 3¹, 45 adjustably limit, in the well known way, the

downward movement of the screw 3, and the 50 follower 1.

By reason of the construction, combination and arrangement of the parts, as shown and described, I am enabled to use the press to obtain the benefit and advantage of a 55 combined screw and foot press. For it will be noted that whether the press is operated by the handle or by the treadle all the parts will act and move unitedly, and the counterweight 4¹ will be caused to swing upon the 60 screw 3 as a pivot within a predetermined arc with velocity dependent upon the speed with which either the handle or treadle are operated, and that its impetus will be suddenly checked at the end of such movement 65 and thereby materially and importantly add to the force and effectiveness of the blow of the follower-carried die upon the piece of work disposed upon the table A in the path of the follower. I am thus enabled to utilize 70 to the fullest extent the benefit and advantage of the impetus and weight of the combined counterweight, follower and treadle to make more effective the operation of my press. This is a novel, important and very 75 useful and advantageous feature of my invention.

I claim:

1. In a press the combination with up- 80 rights provided with guideways and with a cross member connecting said uprights and provided with an internally threaded perforation, of a follower slidably fitted in said guideways and provided with a transverse mediate perforation, an externally threaded 85 screw arranged for operation through said threaded perforation, and operatively connected to said follower, a counterweighted arm carried on the opposite end of said screw and revolvably therewith, and a pend- 90 ent pivotally mounted treadle operatively connected with said follower and arranged and adapted to operate in conjunction with said screw to actuate said follower.

2. In a press, the combination of a screw 95 operated follower for the punch, the operating screw, the die, the counterweighted arm carried on said screw, with a pendent pivot-

ally mounted treadle operatively connected with the follower, and arranged and adapted to operate in conjunction with the counterweighted screw in striking the blow 5 of the die.

3. In a press, the combination of a plunger, a counterweighted screw operatively

connected with said plunger, and a pivotally mounted foot treadle operatively connected with said plunger.

JOHN H. CROWELL.
